APPARATUS FOR PROOFING CARTONS
AND THE LIKE

Carl Wilhelm Hartmann, Lyngby, near Copenhagen, Denmark, assignor to Satona Limited, Edinburgh, Scotland

Application April 27, 1940, Serial No. 332,034
In Great Britain May 24, 1939

7 Claims. (Cl. 91—46)

This invention relates to apparatus for proofing cartons, paper, cardboard or like vessels, and has for its object to enable cartons in quantities to be proofed effectively by a suitable waterproofing composition such as molten wax. Another object of this invention is to provide proofing apparatus adapted to cooperate with conveying means for conveying shaped cartons from shaping machinery, and for conveying cartons to filling or stacking means, so that there is a continuous operation.

According to this invention apparatus for proofing cartons comprises a bath for the liquid proofing substance, a plurality of carton holders arranged in a train and carried by travelling means adapted to feed the holders successively through the bath and to deliver them to collecting means, and means to impart swinging or tilting movements to the cartons relatively to their translative movement when moving from the bath to the collecting means.

In carrying one form of the invention into practice the proofing apparatus is combined with a machine which shapes carton blanks into tubular form with closed bases, the cartons may be of the type which is in use for the retailing of liquids, and which comprises a square section tube with a closed rosette base, and foldable upper parts which are folded into a wedge like mouth closure when the carton is filled. Following the distending of the cartons into open form and the closing of their bases they are delivered into a conveyor having a succession of U shaped clips which individually receive cartons and carry them through a stage which pinches together the sides of the mouth ends of the cartons to ensure that all of the creases and bends appropriate to a finished carton are present prior to the proofing operation so as to avoid fracture or cracking of the proofing material when the carton mouths are sealed.

It is preferred to coat a number of cartons simultaneously and for this purpose a number of fingers are operated to displace laterally relatively to the conveyor with the U shaped clips the desired number of cartons. In the preferred embodiment four cartons are displaced simultaneously by a corresponding number of fingers which have a swinging and translative movement imparted to them so that they remain in contact with the cartons until they are dislodged into a line of carton supports carried by a drum rotating in a casing surmounting the bath.

The said drum is provided with means co-operating with guides on adjacent side frames to impart the before-mentioned swinging or tilting movements to the carton holders so that the surplus wax is substantially evenly drained off the cartons and falls into the subjacent bath.

Scrapers with the conveyor which conveys the

waxed cartons away from the drum can scrape surplus wax from the bases of the cartons.

In order that this invention may be clearly understood and readily carried into effect, drawings are appended hereto illustrating an embodiment thereof, and wherein:

Fig. 1 is a diagrammatic side elevation view of the waxing means, with parts in section this figure chiefly serving the purpose of showing the configuration of the guides appropriate to the said drum, and the relationship of the appropriate stages.

Fig. 2 is a sectional side elevation view showing the waxing bath and mechanism for carrying the cartons to and from it.

Fig. 3 is a part sectional plan of the drum carrying the carton holders.

Fig. 4 is a detail side elevation of one of the carton holders, and

Fig. 5 is a detail plan view of part of the mechanism for actuating carton engaging and releasing means associated with the carton holders.

Referring to the drawings the cartons 1 are of square section and before the waxing stage are supported in double limb or U shaped clips 36 on a conveyor 16 which is seen in sectional elevation in Fig. 2, so that only one limb on each of the adjacent end clips is shown. The upstanding cartons on the top track of the conveyor have been previously partially closed or creased and consequently when they are wax coated the creased parts will be adequately waxed, and the wax in the creases of the cartons will not break away when the cartons are closed after filling. The cartons are in single file on the conveyor 16 and following this pre-creasing the next stage in the operations, which is the subject of the present invention is to deliver the cartons into a wax bath 41 in order to impregnate them with wax and then to manipulate the cartons to ensure adequate and uniform coating.

It is preferred to coat a number of cartons simultaneously and for this purpose a number of fingers 42 are operated to displace laterally relatively to the conveyor 16 the desired number of cartons. In the arrangement shown four cartons are displaced simultaneously by a corresponding number of fingers 42 which have a swinging and translative movement imparted to them so that they remain in contact with the cartons 1 until they are dislodged into an adjacent line of four carton supports 43 carried by a drum 45 rotating in a casing 46 surmounting the bath 41. By way of example eight equi-distantly spaced lines of cartons are shown carried by the drum 45.

The carton supports 43 each comprise four narrow oblong section rods 43a (see Fig. 4) so

that only narrow line contact is made with the cartons. As each set of supports 43 become located at the receiving stage, a cam or abutment 47 carried by a lever 48 rides over a stationary roller 49 and is actuated to transmit movement via a link 50 to a gripping member 51 in the form of a short curved finger located at the base of each support, these fingers being carried by a spindle 51a located across the lower end of each line of supports said spindle 51a being spring loaded in the carton gripping direction of rotation by compression springs 51b. A stop 5c limits the gripping movement.

The levers 48 are supported on short spindles 2 rotating in bosses 3 formed on the side plates or flanges 4 of the drum 45, and the links 50 are connected by cranks 50a on the ends of the spindles 51a. Each line of cartons is supported by a bar 19 supported at its ends by arms 20 depending from the spindles 2.

The wax in the bath is heated by suitable heating means, e. g. an electric heater 41a, and during rotation of the drum 45 the holders are imparted swinging movement by the engagement of rollers 52 and 52a with each set of holders with guide rails 53 (hereinafter more fully described) provided in the casing 46. During the predominating portion of the first half of this arcuate movement of the cartons away from the bath (see Fig. 1) their open ends 10 are lowermost, but when reaching the highest position 11 they are reversed, then again inverted and when ultimately reaching a position immediately above the stage containing the fingers 42 where they are delivered into the bath, they are reversed so that their bases are lowermost at which stage the said abutments 47 engage fixed abutments 49a to move the appropriate gripping members 51 to the carton releasing position. In this latter position a number of carton base engaging abutments 55 with upstanding fingers 56 at their rear ends are passed upwardly relatively to the holders and forwardly towards a conveyor 57 and deposit the appropriate set of cartons on to the upper track of this conveyor. This conveyor which is described in the co-pending application Serial No. 332,029 filed April 27, 1940, has a number of transverse rods 58 equi-distantly spaced and these rods intersect a number of superposed longitudinal guide rails 59 so that in effect the lower end of each carton is supported at its fore and aft walls by a pair of transverse rods 58 and at its lateral walls by a pair of the rails.

The bases of the cartons rest upon a stationary base plate 60 which is provided at several points with heated scrapers 62 to remove surplus wax from the bases of the cartons. At the entrant end of this conveying stage a tray 63 is located in juxtaposition to the upper track of the conveyor to receive wax dripping from the carton.

The arrangement of the said guide rails comprises a lower parallel pair of rails 6 on one side of the casing 46 which receive between them the roller 52 of the appropriate line of holders when the holders descend into the bath and pass arcuately outwards and upwardly from the bath. This lower pair of rails has an entrant stage 6a contained within about 45° of the complete circuit of travel of the holders and which stage is 70 approximately concentric with the axis of the drum, and for a short distance beyond their ends they are curved inwardly as at 6b to afford cam surfaces for the appropriate roller 52 which effect a reversing action to the carton holders so 75

as to bring the cartons right way up before they are transferred to the conveyor 57 which carries the coated cartons to the filling or stacking stage. The empty holders now receive their cartons and 5 pass downwardly along the said approximately concentric part 6a of the guide rails bend downwardly and forwardly producing short radius corners 6c or bends contained in about 20° of the circuit, this resulting in the carton holders 43 being nearly horizontal as they enter into the lowest portion 6d of the guide rails 6, this lowest portion having a large radius and extending through the wax bath. Such lowest portion merges into an outwardly inclined part 6e formed 10 at about 30° to the horizontal plane, and this inclined part merges into an arcuate portion 6f which causes the roller 52 of the appropriate line of holders to impart a swinging movement to the holders so that the base ends of the cartons are 15 above the mouths 10, the cartons being inclined 20 above the horizontal plane containing the axis of the drum and as the roller 52 leaves the guide rails 6 the other roller 52a moves into further rail sections 7 which establish continuity in the sequence of operations with the aforesaid lower portion 6 of the guide rails. This additional portion 7 of the guide rails is on the opposite side 25 of the casing 46 to that containing the rails 6 and is inclined inwardly at about an angle of 45° to the horizontal plane and it has the effect of adding about another 90° swinging movement to the 30 carton holders so that the cartons have their mouths 10 below their bases and the now effective 35 roller 52a trails the now ineffective roller 52 to enable the latter to enter a pair of guide rails 8 resulting in the carton holders swinging to bring the cartons nearly horizontal whereupon the 40 roller 52a enters the lower end of a further short section of guide rail 9, which is also inclined inwardly and upwardly so that its upper end terminates just beyond the vertical plane containing the axis of the drum, this additional guide rail section merging into a relatively short upper 45 horizontal part. Symmetrical with this latter guide rail section is another similar section 10 and the roller 52 of the appropriate line of folders passes into this section 10 as the roller 52a leaves the other 9, the cartons now having their mouths 50 uppermost. A final guide rail section 11 comprises an elongated substantially S shaped section which receives the roller 52a as the roller 52 leaves rail section 10. This section 11 has a lower end from which the roller 52a of the holders 55 passes to free the cartons on to the appropriate conveyor 57, this final section of the guide rails imparting nearly a semi-circular movement to the cartons. As the roller 52a passes from the rail section 11, the other roller 52 is brought opposite the entrant end of the section 6 ready to 60 re-commence the cycle operations.

The rollers for travelling in the guide rails are arranged one pair for each set of carton holders, the pair of rollers being carried at the ends of two arms 13 and 14 fixed on the spindles 2 one at each end of each line of holders, each pair of arms being arranged V fashion in end elevation as shown in Fig. 2, only one roller at a time engaging in the appropriate rail section, and as a roller leaves one rail section the other roller engages in the next rail section.

The drum 45 is imparted an intermittent rotation by Maltese cross or other suitable driving means 15, the conveyors 16 and 57 likewise being

moved intermittently so that both conveyors and the drum 45 move in the required sequence. A platform 17 guides the cartons from the conveyor 16 into the holders, the outermost of the rods 43a of the holders being shorter than the others, as indicated at 43b in Fig. 2 to enable the cartons to be guided properly into the holders.

By means of the foregoing apparatus cartons are adequately coated with proofing material and agitated to such an extent as to release most of the surplus wax or other proofing material into the bath.

I claim:

1. Apparatus for proofing cartons comprising a rotary conveying structure, a plurality of carton supports carried by said structure and arranged to be traversed in a substantially circular endless path by the conveying structure, a wax bath subjacent to said structure adapted to receive the cartons at the lowest point of their travel, means imparting orbital movements to the carton supports during their travel, carton collecting means above the bath adapted to receive the coated cartons and means in juxtaposition to the bath and immediately subjacent to said collecting means to feed non-coated cartons into empty holders.

2. Apparatus for proofing cartons comprising a rotary conveying structure rotating intermittently on a horizontal axis, a plurality of carton supports carried by said structure, means to impart predetermined orbital movements to the supports during rotation of said structure, a wax bath arranged beneath said structure and through which said supports are adapted to be drawn by the rotation of the structure, means in juxtaposition to the bath operating during the stationary periods of the rotating structure to automatically feed cartons into the supports before the supports enter the bath, and means spaced substantially immediately above said feeding means adapted to automatically remove the coated cartons from said supports.

3. Apparatus for proofing cartons comprising a rotary conveying structure adapted to be rotated intermittently on a horizontal axis, a plurality of carton supports carried by said structure and each adapted to accommodate a carton, means to impart predetermined orbital movements to the supports during rotation of said structure, a wax bath arranged beneath said structure and through which said supports are adapted to be drawn by the rotation of the structure, means in juxtaposition to the bath operating during the stationary periods of the rotating structure to automatically feed cartons into the supports before the supports enter the bath, means spaced substantially immediately above said feeding means adapted to remove the coated cartons from said supports, a delivery stage gripping means with said supports automatically gripping the cartons externally when they are received in the supports and maintaining the cartons in the supports until they have traversed the bath and reached the delivery stage and means adapted to automatically actuate the gripping means to release the cartons when the carton supports reach the delivery stage.

4. Apparatus for proofing cartons comprising a rotary conveying structure, a plurality of carton supports carried by said structure and arranged to be traversed in a substantially circular

endless path by the conveying structure, a wax bath subjacent to said structure adapted to receive the cartons at the lowest point of their travel, means imparting orbital movements to the carton supports during their travel, carton collecting means above the bath adapted to receive the coated cartons, means in juxtaposition to the bath and to said collecting means to feed non-coated cartons into the empty carton supports, carton gripping fingers at the bases of the carton supports adapted to grip against the exterior of the cartons, levers operatively connected to said fingers, and abutments adapted to be operatively engaged by said levers located adjacent to the entrant side of the bath and to said collecting means.

5. Apparatus for proofing cartons comprising a rotary conveying structure, a plurality of carton supports carried by said structure and arranged to be traversed in a substantially circular endless path by the conveying structure, a wax bath subjacent to said structure adapted to receive the cartons at the lowest point of their travel, means imparting orbital movements to the carton supports during their travel, carton collecting means above the bath adapted to receive the coated cartons, means in juxtaposition to the bath and to said collecting means to feed non-coated cartons into the empty carton supports, carton gripping fingers at the bases of the carton supports adapted to grip against the exterior of the cartons, oscillatable levers carried by said supports and adapted to swing said fingers to carton freeing positions, an abutment adjacent to said collecting means adapted to be engaged by said levers to effect said freeing operation, and spring means yieldingly opposing the movement of said levers and fingers to the carton freeing position.

40 6. In a carton proofing apparatus a plurality of oscillatable carton holders, rotary supporting means for said holders, a wax bath beneath the supporting means adapted to have the cartons traversed therethrough, two sets of cam-like guides located at opposite sides of said supporting means, pivoted supports for the carton holders in said supporting means, rocking arms fixed to said pivoted supports adapted to impart oscillation to said holders and operatively engaged with said cam-like guides, means located in juxtaposition to the entrant side of said bath automatically feeding cartons into the said holders, and means automatically freeing the cartons from the holder immediately above said feeding means.

45 7. In a carton proofing machine a wax bath, a rotary conveyor above said bath, a plurality of carton holders oscillatably carried by said conveyor and each comprising a number of spaced narrow rods having edge contact with the cartons, spring loaded carton gripping fingers carried by said holders, means adjacent the entrant side of the bath imparting movement to said fingers against influence of their spring means 50 to free the cartons, cam-like guides on opposite sides of the rotary conveyor, pivoted supports for said carton holders in said conveyor and levers fixed to said pivoted supports and engaged with and adapted to traverse said cam-like guides adapted so as to impart oscillation to said holders.

CARL WILHELM HARTMANN.
